PULSED HIGH FREQUENCY ELECTRO- THERAPEUTIC UNIT

William Denis Kendall, Los Angeles, Calif., assignor to
Dynapower Systems Corporation, Los Angeles, Calif.,
a corporation of Delaware

Filed Apr. 17, 1962, Ser. No. 69,751

Term of patent 14 years

(Cl. D83—1)

FIG. 1 is a front perspective view showing the left side of a pulsed high frequency electrotherapeutic unit embodying my new design; and

FIG. 2 is a rear perspective view showing the right side of the unit.

I claim:

The ornamental design for a pulsed high frequency electrotherapeutic unit, substantially as shown.
